UNITED STATES PATENT OFFICE.

FRANCIS S. INCO, OF LOS ANGELES, CALIFORNIA.

FOLDING PORTABLE BED.

Application filed May 24, 1922. Serial No. 563,241.

My invention relates to the manufacture of beds, and has for its principal object to provide a portable bed which may be folded so as to occupy a small space and which will be of such size and shape when folded that it may be easily concealed.

It is also an object of my invention to provide in such a folding bed when folded, a low center of gravity, so that the folded bed may be conveniently moved about.

It is also a further object of my invention to provide a folding bed in which the parts are so connected and balanced that the legs thereof are self-adjusted to correct supporting position as the bed is unfolded said legs being always dependent.

It is a still further object of my invention to provide an improved foot rail and mattress gripping structure.

The specific advantages of the invention and further objects thereof will be made evident hereinafter.

Referring to the drawings, which are for illustrative purposes only,

Fig. 1 is an extended side elevation of a bed structure embodying my invention.

Fig. 2 is a plan view of the bed shown in Fig. 1.

Fig. 3 is an elevational view showing the foot section of the bed structure raised into vertical position to illustrate the manner in which the supporting legs are withdrawn into retracted position as the bed is folded.

Fig. 4 is an elevational view illustrating the foot section of the bed structure folded back over the head section thereof.

Fig. 5 is an elevational view illustrating the bed structure in erect position upon the carriage which is provided therefor.

As shown in Figs. 1 and 2 of the drawing, my invention provides a carriage 11 comprised of a pair of end frames 12 which are shown as rounded to form arms and which are provided with castors 13 so that the carriage may be wheeled about, the end frames 12 being connected by a laterally extending angle 15 which is fastened to the under side of cross bars 16 provided upon the end frames, and is reinforced thereto and braced

in an intermediate position by diagonal bars 17. A head section 18 comprised of a pair of side angles 19 connected at their rearward ends by an end angle 20 is pivoted to the carriage structure at 21 and adapted to project in opposite directions thereover. A foot section 23 formed of a pair of side angles 24

connected at their forward ends by a foot angle member 25 is linked to the head section 18 by a pair of short angles 27 constituting a middle section. A spacer member is provided between the links 27 in the form of a yoke 28 which has the ends 29 thereof upwardly bent and pivotally connected centrally to the link 27 at 30. From a pivot 31 upon the ends 29 of the yoke 28, intermediate supporting legs 33 are mounted, these legs 33 being connected to the carriage 11 by a link 34.

Foot legs 36 are pivoted at 37 to the side angles 24 of the foot section 23 and the upwardly extending ends 38 of the legs 36 are connected to pivots 39 upon the connecting links 27 by link bars 40 which I have provided as a retractive means for the legs 36 which withdraws these legs as the bed structure is folded. A spring fabric 41 is extended across the rectangular frame provided by the angles comprising the head and foot sections and provides a support for the mattress.

A head panel 45 is pivoted at 46 to upwardly extended posts 47 mounted at the extreme rearward ends of the side angles 19 of the head section and is linked to the carriage 11 by members 48. Also, a foot panel 50 is pivoted upon the foot section at 51, this panel 50 comprising an upright portion 52 having inwardly projecting plates 53 extending therefrom by which the pivoting of the foot panel to the foot section is accomplished. As shown in Fig. 3 of the drawing, this foot panel 50 is adapted to swing inwardly upon the pivot 51 and down upon the mattress 55, as indicated at 56. Springs 57 connecting between the plates 53 and the side angles 24 provide a means for holding the foot panel 50 forcibly down upon the mattress, thus firmly gripping the mattress so that it cannot become displaced when the foot section 23 is raised into the vertical position, as shown in Fig. 3, which constitutes the first step in folding the bed. As the foot section is lifted, the links 40 are exerted against the ends 38 of the legs 36 and these legs are thereby caused to swing inwardly, as indicated by the arrow 58 in Fig. 1, coming to rest in the retracted position in which they are shown in Fig. 3.

The next step in folding the bed consists in swinging the foot section inwardly, as indicated by the arrow 60, so that it will assume the position in which it is shown in Fig. 4. The links 27 are so mounted upon

the ends of side angles 19 and 24 that these parts cannot be folded to assume a lesser angle than 90°, therefore, as the foot section is swung over upon the head section, the links pivot on the points 61 and assume the vertical position shown in Fig. 4 and cause the yoke 28 and the intermediate legs 33 to be lifted and to assume the position shown in that figure. With the parts of the bed structure in this position, the mattress supporting structure is then lifted, as indicated by the arrow 65 in Fig. 4, causing it to turn upon the pivot 21 and to assume the vertical position shown in Fig. 5. As the structure is so swung, link members 48 cause the head panel 45 to be swung inwardly, as indicated by the arrow 68 in Fig. 4, so that when the vertical position of the structure is assumed the head panel is in a position enclosing the lower end 69 of the foot section, thus preventing the foot section from swinging outwardly when the bed structure is in the erect position. In other words, the member 48 provides a parallel link arrangement between the carriage 11 and the head panel 45 so that the panel is always maintained in a vertical position. Also, as the bed is swung into vertical position, the links 34 draw the intermediate legs 33 and the yoke 28 into the retracted position shown at 75 in Fig. 5.

It will be perceived from Fig. 5 that the folded bed occupies but comparatively small space and is particularly adapted to be concealed in articles of furniture, such as a davenport, or in a suitable cavity provided in the wall construction of the house. This bed may be easily wheeled about as its center of gravity is very low, and there is but little danger of its being overturned, the entire height of the structure for a standard length bed being less than 36 inches. Furthermore, the parts are so arranged and bal-

anced that the bed may be unfolded with but little exertion, thus particularly adapting the bed to being handled by women and children. 15

I claim as my invention:

1. In a folding bed of the class described, the combination of: a carriage; a head section pivoted upon said carriage in such manner as to project beyond the same when extended; a foot section; links pivotally connecting said foot section to said head section by separate pivots at the respective ends thereof; foot legs pivoted to said foot section; spacer means extending between said section connecting links; intermediate legs pivoted to said spacer means; links extending between said foot legs and said connecting links for retracting said foot legs as said foot section is raised; and links extending between said intermediate legs and said carriage for retracting said intermediate legs as said head section is raised and for holding said legs always dependent. 55 60 65

2. In a folding bed of the character disclosed, the combination of: a supporting structure; a head section pivoted upon said supporting structure; a foot section; links pivotally connecting said foot section to said head section; a spacer yoke pivoted at its ends to said links; intermediate legs pivoted to said yoke; foot legs pivoted to said foot section; links connected to said foot legs and said links for retracting said foot legs as said foot section is raised; and links connecting said intermediate legs and said supporting structure for retracting said intermediate legs when said head section is raised. 70 75

In testimony whereof, I have hereunto set my hand at Los Angeles, California, this 17th day of May, 1922. 80

FRANCIS S. INCO.
